DON D. MYERS, OF TOLEDO, OHIO, ASSIGNOR TO INDUSTRIAL RESEARCH CORPORATION, OF TOLEDO, OHIO, A CORPORATION OF DELAWARE.

WASHING AND DRYING MACHINE.

Application filed October 21, 1920. Serial No. 418,353.

This invention relates to improvements in washing machines, and has for its general object the provision of a washer in which the cage containing the articles to be washed is reciprocated to agitate said articles for washing, and in which the cage is raised above the surface of the liquid and rotated to wring the articles by the action of centrifugal force.

10 Other objects of my invention are:

To provide simple automatic means for accomplishing the above operations; to provide simple means to elevate the cage above the surface of the liquid and to automatically connect it so as to rotate it at high speed; to provide means to raise the cage at a slower rate than it is lowered during the reciprocations of the washing operation whereby the power requirements of the machine are made 20 more uniform and also the agitation made more efficient for washing; to provide means for throwing the mechanism into "neutral" to stop the motion of the cage at any time; to provide new and improved means for attaining the above objects.

Other objects and those relating to simplicity and lightness of structure and economies of manufacture will appear herein as I proceed with a detailed description of that 30 particular embodiment of my invention which for the purposes of illustration I have shown in the appended drawings, in which,

Figure I is vertical section showing the machine during the washing operation, the belt shifter being on the point of shifting the belt to the dotted position to elevate the cage.

Figure II shows the machine during the wringing operation, the belt being held in one position. The operating mechanism is 40 shown in elevation.

Figure III is a section on line 3—3 of Figure I.

Figure IV is a sectional view on line 4—4 of Figure I.

Figure V is a sectional view on line 5—5 of Figure II.

Figure VI is a sectional view on line 6—6 of Figure I.

50 Figure VII is a plan view of the control latch mechanism.

Figure VIII is an elevation of the control latch mechanism, showing its three positions.

55 Similar reference characters refer to simi-

lar parts throughout the several views.

1 represents a stationary tub within which is arranged a rotatable and reciprocatable cage 2 for holding the articles to be washed. The cage 2 is constructed of some 60 previous material such as perforated sheet metal, wire netting or screening, etc., and is suitably supported and driven by a central vertical shaft 3. The tub 1 is here shown as having in the center of its bottom an up- 65 standing guide 4 for the shaft 3 which extends up above the surface of the water and thus renders it unnecessary to have leak proof packing about shaft 3. The shaft 3 is fastened to the cage 2 by means of a center casting 5 which is secured to the bottom of cage 2 and telescopes over the center guide 4 when the cage is reciprocated up and down.

The driving mechanism for shaft 3 will 75 now be described. Shaft 3 is supported at its lower end by a stepped pulley 10 which is screw threaded upon shaft 3 as shown in Figure I. Pulley 10 is supported upon the rotatable member 11 of a thrust bearing 12 80 by means of a sleeve 13 which may be integral with the pulley 10 as shown. Pulley 10 also is provided with a similar sleeve 14 at its upper end and which engages a thrust bearing 15 when the pulley 10 is thrust upward by the reaction of pulling shaft 3 85 downward. A loose pulley 17 runs on the sleeve 14 and its weight is supported by a shoulder on pulley 10. A larger loose pulley 16 runs on the lower sleeve 13 and its 90 weight is preferably supported by the rotatable member 11 of the thrust bearing. Pulleys 16 and 17 may be provided with bushings 18 and 19 respectively, as shown in Figure I. The screw pulley 10 has a portion 9 95 of equal diameter with pulley 17 and a portion 8 of equal diameter with pulley 16. The three pulleys 17, 10, and 16 may be provided with lubricating oil pockets and oil ducts leading from one to the other and with overlapping flanges to direct the oil from one to the other so that all the pulleys and the two thrust bearings 15 and 12 may be oiled from one source. The oil finally finds its way 100 down into the space 20 within the pedestal 21 which supports the thrust bearing 12. The lower end of the screw threaded portion 22 of shaft 3 is provided with a collar 23, which strikes the rotatable member 11 when the shaft is screwed upward by pulley 10 and 105

110

acts as a stop to prevent the shaft 3 from further elevation. The shaft 3 with the cage 2 will then be rotated by pulley 10 by the driving connection through the threads. 5 The belt shifting mechanism will now be described.

A motor 30 drives the pulley 10 through a belt drive as shown in Figure III. An auxiliary shaft 31 containing the loose pulleys 32, 33, and 34 is fastened to an arm 35 which is arranged to be pivoted at 36 which pivot is in a horizontal plane including the center of the motor pulley 37 and the center line of shaft 3. (See Figure II.) With this 10 arrangement shaft 31 may swing in a small arc about its pivot 36 without tightening or loosening the belt an excessive amount. When shaft 31 is in position shown in Figure I, the belt on pulley 34 rotates loose pulley 16 in one direction and the threaded driving pulley 10 in the opposite direction as shown by the arrow. The driving pulley 10 is thus drawing shaft 3 downward since shaft 3 is prevented from rotating by a means later 15 herein described. Just before the unthreaded portion of shaft 3 engages the driving pulley 10, the direction of rotation of the driving pulley is reversed by shifting shaft 31 upward, which shifts the belt on pulley 16 to the face 8 of driving pulley 10, and the belt on face 9 to the loose pulley 17, which belt positions are shown in dotted lines in 20 Figure I. The driving pulley 10 then rotates in a direction to raise shaft 3. A collar 40, rigidly attached to shaft 3 has a head 41 clamped thereto by means of spring clamps 42. Head 41 also has a stationary guide member 44 (see Figures II and VI) which extends upward from the part 45 of 25 the stationary frame which holds the upper thrust bearing 15. The part 45 may be bracketed to the pedestal 46 which supports the pivot 36, however the bracket is cut away, as shown in Figures II and III, in 30 order to show other parts more clearly. Rigidly attached to the head 41 is the extension 50, which slidably supports the shift rod 51 through two adjustable stops 52. The lower end of shift rod 51 reciprocates 35 in a forked end 53 of a rock arm 54 which is also pivoted at 36 where arm 35 is pivoted. The shift rod 51 is provided with two adjustable stops 55 and 56 above and below the fork 53 of rock arm 54. Now when shaft 40 40 is raised by the drive pulley 10, the collar 40 raises the head 41 which in turn raises the shift rod 51. The lower stop 55 raises the lower end of rock arm 54 (see Figure I) until its opposite end 57 45 is a little past dead center of pivot 36 and the shaft 31. A long tension spring 60 is suitably attached to the end 57 and the shaft 31, and therefore as soon as the end 57 is past dead center, the force of spring 60 will 50 first snap the fork 53 against the upper stop

56 and then shift the shaft 31 downward through its pivoted arm 35. Thus the belt is again shifted downward to the position shown in full in Figure I and the drive pulley reversed to lower the shaft 3. Thus it 70 is seen that the shaft 3 with the clothes cage 2 is automatically raised and lowered with the motor running continuously in one direction. This motion of the cage 2 in the hot suds in the tub 1 accomplishes the washing, 75 the best speed of the reciprocations of the cage being determined by experiment and the machine operated accordingly. It will be seen that the driving pulley 10 is run faster when the cage 2 is being lowered 80 than it is when it is being raised. This gives a less variation of load on the motor as well as accomplishing a better washing operation.

The wringing operation will now be described. 85

A lug 61 on the end of arm 35 is adapted to catch in a notch 62 in a flap 63 when the flap is turned toward the lug by means of the control handle 64. (See Figures II and VII.) During the washing operation the 90 flap 63 is turned aside by placing the control handle in notch 65 as shown in Figure I. If the control handle is placed in notch 67 (see Figure II) the flap will be turned toward lug 61 and the notch 62 will be in a 95 raised position. Springs 68 attached to the projections 69 on flap 63 (see Figure III) will allow the handle 64 to turn and be placed in notch 67 while flap 63 is being pressed against lug 61 by the force of the 100 springs 68. Now as soon as the shaft 31 is raised to its high position the lug 61 will snap into the notch 62 and thus the shaft 31 will be retained in its high position and further shifting of the belts prevented. Therefore the shaft 3 will continue to be elevated until cage 2 is beyond the surface of the water (see Figure II) until finally the collar 105 40 strikes the rotating member 11 of the lower thrust bearing. In the meantime the 110 collar 40 raises head 41 until it strikes the stationary cams 70 on the levers 71 which are pivoted to the stationary part 45 of the frame, thus forcing levers 71 outward and withdrawing the attached spring clamps 42 115 to release the head 41 from engagement with collar 40. Collar 40 then continues upward until it strikes the arm 75 of a bent lever pivoted on the stationary pin 76 (see Figure II). The other arm 77 engages a 120 brake lever 78 and releases a brake band 79 from its drum 80. The drum 80 is splined to shaft 3 so that when the drum 80 is held stationary shaft 3 may be raised or lowered but is held from rotating. However when 125 the brake band is released the drum 80 is allowed to rotate with shaft 3. The collar 40 releases the brake a short time before the upward movement of shaft 3 is stopped by the collar 23 at its lower end, and thereafter 130

the cage 2 begins rotating, gradually at first due to the inertia of the cage and clothes and then at the full speed of the drive pulley after collar 23 strikes member 11. The water in the clothes is forced out of the clothes in the cage by centrifugal force due to the high speed of rotation.

After the clothes have been sufficiently wrung the control handle is shifted to the notch 66 without turning it enough to release lug 61. This places notch 62 in a position to hold the lug 61 so that shaft 31 is midway between its top and bottom positions. When shaft 31 is in this position the belt runs on both the top loose pulley 17 and the bottom loose pulley 16 but not on the drive pulley 10. Therefore the mechanism is in "neutral" and the motion of shaft 3 will cease. The clothes may then be removed and the cycle of operations repeated. It will be noted that the mechanism may be thrown into neutral at any time during the washing operation simply by shifting the control handle to the detent notch 66. Then as soon as the lug 61 is moved past its middle position it will snap in the notch 62 and be held there, thus throwing the belt to neutral position instead of shifting it all the way to reverse drive. It will be noted that when shaft 3 is rotated by drive pulley 10 to lower it from the drying position that the weight of the clothes, cage and shaft is sufficient to cause shaft 3 to descend as well as rotate in the opposite direction. When the cage descends from its drying position the collar 40 on releasing the bent lever 75 allows brake band 79 to grip drum 80 and prevent further rotation of shaft 3. When collar 40 descends until it contacts with the spring clamps 42 it rides over the upper beveled edges of clamp 42 thus pressing them apart until it snaps into position in the grooves in the clamps. The machine will then begin the reciprocating motion when control handle 64 is thrown in the detent notch 65.

While I have shown and described in detail a certain form of mechanism for imparting a reciprocating motion to the cage 2 during the washing operation and a rotary motion during the wringing operation other automatic forms of mechanism may be devised or this form have various improvements and modifications without departing from the scope of my invention. Various other modifications than the particular embodiment illustrated will be obvious to those skilled in the art and the scope of my invention is defined by the appended claims.

What I claim is:

1. In a washing machine, a vessel for containing a fluid; a clothes cage movable within said vessel; a single control handle adapted to be set in a plurality of positions; means to drive said machine; means controlled by the position of said handle to

connect and disconnect said driving means and said machine; means to reciprocate said cage to wash the clothes therein; means to raise the cage above the liquid in said vessel and to rotate said cage when so raised to wring the clothes therein by centrifugal force; and means to lower said cage into reciprocating position, said reciprocating means, raising and rotating means and said lowering means, being controlled by the position of said handle.

2. In a washing machine, in combination a vessel for containing a fluid; a clothes cage movable within said vessel; and means for reciprocating said cage at a uniform speed up and a uniform speed down for agitating the clothes within said cage.

3. In a washing and wringing machine in combination a vessel for containing a washing fluid; a clothes cage movable within said vessel; means actuated by a uniformly actuated power source for reciprocating said cage in a substantially vertical direction at a greater speed in one direction than in the other for the purpose of washing the clothes in said cage; means to raise said cage above the washing fluid; and means to rotate said cage when so raised to wring the clothes therein by centrifugal force.

4. In a washing machine, in combination, a vessel for containing a fluid; a clothes cage movable within said vessel, and means for reciprocating said cage at a uniform speed up and at a greater uniform speed down for agitating the clothes within said cage.

5. In a washing machine, in combination, a vessel for containing a fluid, a clothes cage movable within said vessel, a screw threaded means to move said cage up and down, a power source, and automatic means to cause said power source to rotate said screw threaded means in intermittently reversed directions.

6. In a washing machine, the combination of a receptacle for containing a fluid, a perforated casing movable within said receptacle, screw-threaded means for moving said casing, mechanism for operating said screw-threaded means in intermittently diverse directions, means for raising the casing above fluid contained in the receptacle and rotating the same, and single power means associated with said casing and receptacle and adapted to cause reciprocation and rotation of said casing during different stages in the operation of the mechanism.

7. In a washing machine, the combination of a liquid containing receptacle, a perforated casing positioned within said receptacle and adapted to have vertical reciprocatory movement therein, mechanism for reciprocating said casing, mechanism for rotating said casing, single power means adapted to actuate said mechanism to cause reciprocation of the casing within the receptacle and

rotation of the casing within the receptacle, and control means for establishing connection between the power means and said mechanism.

5 8. In a washing and wringing machine, a vessel for containing a fluid; a base for supporting said vessel; a clothes cage movable in said vessel; a central shaft for supporting said cage; means to raise said shaft until

said cage is above the fluid in said vessel; 10 means to rotate said shaft and cage to wring the clothes therein by centrifugal force; a bearing for said shaft attached to said vessel and a second bearing for said shaft attached to said base.

15 In testimony whereof, I affix my signature.

DON D. MYERS.
